LOOSE-LEAF BINDER

Ralph P. Bifaro, 124 Oak St., Yonkers, N.Y.

Filed Jan. 27, 1964, Ser. No. 78,358

Term of patent 3½ years

(Cl. D6—2)

FIG. 1.

FIG. 2.

FIG. 3.

FIG. 4.

FIG. 5.

FIG. 6.

FIG. 2 is a front view thereof;

FIG. 3 is a rear view thereof;

FIG. 4 is an end view thereof;

FIG. 5 is a bottom plan view thereof; and

FIG. 6 is a top plan view thereof.

The broken lines illustration in FIG. 1 of the ruler and writing instruments is merely for illustrative purposes.

I claim:

The ornamental design for a loose-leaf binder, as shown and described.
